(57) **CLAIM**

The ornamental design for a brake lining for railroad vehicle, as shown and described.

DESCRIPTION

FIG. 1 is a front elevation view of a brake lining for railroad vehicle.

FIG. 2 is a rear elevation view thereof.

FIG. 3 is a top plan view thereof.

FIG. 4 is a bottom plan view thereof.

FIG. 5 is a right side elevation view. A left side elevation view is a mirror image of the right side elevation view.

FIG. 6 is a referential perspective view showing the location of this article and the inner side of a brake disc; and,

FIG. 7 is a referential perspective view showing the location of this article and the outside of a brake disc.

(Continued)

The broken lines shown in the drawings illustrate the environmental structures that form no part of the claimed design.

1 Claim, 7 Drawing Sheets
